VENETIAN BLIND AND MEANS FOR LOCKING THE SAME

Filed March 12, 1949

UNITED STATES PATENT OFFICE

2,523,392

VENETIAN BLIND AND MEANS FOR
LOCKING THE SAMELeib Rabinowitz and Abraham Rabinowitz,
Brooklyn, N. Y.

Application March 12, 1949, Serial No. 81,116

1 Claim. (Cl. 160—172)

1

This invention relates to Venetian blinds, and the main object is the provision, in combination with the slats of which the blinds are made up, of locking means whereby the blinds may be locked in fully extended position so that the window may be left open without danger of an intruder being able to get in through the window, as well as for other purposes.

The above broad as well as additional objects will be clarified in the following description, wherein characters of reference refer to like-numbered parts in the accompanying drawing. It is to be understood that the drawings are intended solely for the purpose of illustrating the invention, and it is therefore to be understood that it is not intended or desired to limit the invention necessarily to any or all of the exact details shown except insofar as they may be deemed essential to the invention.

Referring briefly to the drawing, Fig. 1 is a perspective view of a window equipped with a Venetian blind and showing an embodiment of the invention applied thereto.

Fig. 2 is a sectional view taken on the line 2—2 of Fig. 1.

Fig. 3 is a fragmentary perspective view of a Venetian blind and one of the two upright guide members which are mounted on both sides of the window frame.

Fig. 4 is a perspective view substantially similar to Fig. 3 but also showing the releasable locking member in locking position.

Fig. 5 is a fragmentary perspective view of the releasable locking member per se.

Fig. 6 is a sectional view taken on the line 6—6 of Fig. 4.

Referring in detail to the drawing, the numeral 10 indicates a window frame having the opposed walls 11 and 12 and the sill 13, the sashes 14 and 15 being mounted therein in the usual manner. A Venetian blind 16 is also shown mounted on the window, for operation in the usual manner, and its plurality of horizontal slats is shown at 17.

In carrying out the objects of this invention, a pair of upright hollow moldings 18 are mounted against the side walls 11 and 12 of the window frame. Each molding 18 is provided with coplanar wings 19 having a series of vertical spaced circular openings 20 therethrough, each of the said openings 20 having a reduced slot-like extension 21. The moldings 18 may thus be attached to the walls 11 and 12 by first screwing screws 22 in proper vertically spaced positions in these walls and leaving the screw heads projecting slightly from the walls, then setting the

molding against the wall with the screw heads passing through the openings 20 in the wings 19, and finally sliding the moldings down so that the screw stems enter the slot extensions 21. Thus the moldings 18 may readily be mounted in place or removed. Of course any other suitable or desired means of attaching the moldings 18 may be utilized without altering the scope of this invention. The moldings 18 are so positioned that their lower ends stand a short distance above the sill 13, thus leaving a clear space 23 between the lower end of the molding and the sill or whatever other member of the entire window frame may lie below the molding.

15 Each molding 18 has a vertical median slot 24 extending upward through the lower end of the middle wall or panel 25 thereof and terminating a short distance from the top of the said panel, as shown in Fig. 3, thereby leaving a portion 26 of the panel at the top serving to close the upper end of the slot 24.

20 Each of the slats 17 is provided with outwardly extending pins 27 which may be provided on the ends of the slats in any desired manner. One way of securing the pins is illustrated in Fig. 3, by having the pins integral with end caps 28 frictionally mounted on the ends of the slats. These pins project through the slots 24 in the moldings 18.

25 That wall 29 of each molding 18, which faces forward into the room, is provided with a series of equally spaced openings 30, which may be square in conformation, therethrough, these openings being so positioned that each is on a horizontal level between the slats 17 when the blind is fully extended across the window opening.

30 A locking member comprises a bar 31 equal substantially in length to the height of the moldings 18, and two such locking members are utilized, one for each side of the window. The bar 31 is provided with a plurality of spaced projections or prongs 32 lying in a common plane and so arranged that the distance between adjacent prongs is equal to the distance between adjacent openings 30 in the molding wall 29. Thus, when the blind is fully extended, insertion of the prongs into their respective openings 30 and pushing the bar 31 home against the wall 29, causes the prongs to be positioned between the slat pins 27, as shown in Fig. 6. In this position of the bar 31 and hence the prongs 32, it is apparent that the blind cannot be raised or folded up, for the prongs 32 serve as obstacles which the pins 27 cannot pass. Hence the blind cannot

be raised by any person on the outside of the building.

The bar 31 is provided with a handle intermediate its length for easy handling and positioning the bar. Any suitable means may be provided for releasably locking the bar 31 in the position shown in Figs. 4 and 6, and one such means is illustrated. This consists in mounting the handle 34 pivotally in brackets 35 on the bar, and further having a right-angle-shaped tongue 36 hinged at one end at 37 to the adjacent wing 19 and having a slot or opening 38 through its other end adapted to receive a padlock 39. Thus, the bar 31, Fig. 4, cannot be removed to free the slat pins 27 without first unlocking the lock 39 and 10 pivoting the handle 34 out of the way of the tongue 36.

Obviously, modifications in form or structure may be made without departing from the spirit or scope of the invention. The spaces 23 below the moldings 18 permit of withdrawing of the pins 27 when it is desired to remove the blind.

We claim:

In combination with a window equipped with a Venetian blind, said window including a window frame having opposed side walls, said blind including a plurality of horizontal slats, each of said slats having pins extending from the ends thereof, a hollow vertical molding mounted against each of said side walls, said pins all lying in a common vertical plane, said molding including a wall at right angles to said pins, said wall having a vertical slot therethrough, said pins adjacent said each of said side walls projecting through said slot into said molding, said molding having a front wall at right angles to said slotted wall, said front wall having a plurality of vertically spaced openings therethrough, the distance

between adjacent of said openings being substantially equal to the distance between adjacent of said slats when the blind is fully extended, each of said openings being positioned between the horizontal positions occupied by said slats when the blind is fully extended, a bar having a plurality of spaced prongs extending from one side thereof, the distance between adjacent of said prongs being substantially equal to the distance between said openings as aforementioned, said bar being adapted to be positioned against said front wall with said prongs passing through said openings and positioned between said pins, means for locking said bar releasably in said position against said front wall, said means comprising a U-shaped handle pivotally mounted on said bar, a hasp tongue pivotally mounted at one end on said molding, the other end of said tongue having an opening therethrough, said tongue being adapted to be swung into position across said bar, said handle being adapted to be swung into position over said tongue so that said tongue passes under said handle, said tongue opening being adapted to have the hasp of a padlock passed therethrough.
